UNITED STATES PATENT OFFICE.

ALONZO B. CLARK, OF GARDNER, MASSACHUSETTS.

IMPROVEMENT IN SEATS AND BACKS FOR CHAIRS.

Specification forming part of Letters Patent No. 132,951, dated November 12, 1872.

To all whom it may concern:

Be it known that I, ALONZO B. CLARK, of Gardner, in the county of Worcester and State of Massachusetts, have invented a new and useful Improvement in the Seats and Backs of Chairs, of which the following is a full, clear, and exact description, reference being had to the accompanying drawing making part of this specification, in which—

Figure 1 is a perspective view of a chair-seat frame with my improved seat applied thereto. Fig. 2 is a perspective view of the frame of a chair-back with my improved back applied thereto. Fig. 3 is a section on the line *x x* of Fig. 1, showing the manner of securing my improved seat in place; Figs. 4 and 5, modifications of my method of securing the same.

My invention consists in a paper seat or back applied to the frame of the seat or back of a chair, stool, lounge, or settee, the paper being of sufficient thickness and possessing the requisite degree of strength and durability, while, at the same time, it is much less expensive than any of the other materials ordinarily used for this purpose.

To enable others skilled in the art to understand and use my invention, I will proceed to describe the manner in which I have carried it out.

In the said drawing, A represents a chair-seat frame, which is provided with a shoulder, *a*, extending entirely around its upper inner

edge, the depth of the shoulder being made equal to the thickness of the paper seat B, so that its upper surface will lie flush with the upper surface *b* of the frame. The size of the paper seat is made to conform to and snugly fit the opening in the frame, and is held securely in place upon the shoulder *a* by tacks, nails, or screws *c*, either countersunk or not, Figs. 3 and 4. When the fastenings are countersunk the paper seat is provided with recesses for the reception of their heads, after which a thin strip of paper or other material of any color may be pasted or glued over them and the seat to give a finished appearance to the work, Fig. 1. Round-headed ornamental fastenings may also be employed, if desired, as seen in Fig. 4. Another way of securing the paper seat or back C to its frame is shown in Fig. 5, the paper in this case being bent over an inner frame, *d*, and then both fastened inside the outer frame *e* by screws *h* passing through the sides or otherwise.

What I claim as my invention, and desire to secure by Letters Patent, is—

A paper seat or back for chairs, stools, settees, &c., substantially as described.

Witness my hand this 28th day of September, A. D. 1872.

ALONZO B. CLARK.

In presence of—

D. T. CRESSEY,
E. B. CLARK.
